FILING SYSTEM

Stephen J. O'Hara, Oakland, Calif.

Application November 29, 1944, Serial No. 565,703

4 Claims. (Cl. 129—18)

This invention, a filing system and means for filing papers and documents of all kinds, particularly business, legal and similar forms, is an improvement over conventional filing systems in that, though only a single securing member or filing post is used, papers of any and all sizes and weights can be filed together with the assurance that alignment of the various papers and sheets will be maintained; any of the papers can be removed or replaced at will without disturbing other papers; and, because of the reinforcement of the paper about its securing area, papers are not readily damaged and will maintain their positions in the file.

The system and means is applicable to all types of documents and papers, such as letters and copies, invoices, statements or any other type of paper or document within the limits of the covers, because punching and reinforcing can be carried out after the paper or document has been written, filled in, or otherwise completed.

In conventional filing systems, two or more filing posts are used to keep the papers in line, and obviously, because of the spacing of the posts, any papers which are shorter than the distance between two posts cannot be maintained in alignment with the other papers in the file.

Because of the unusual shape of my filing post and of the reinforced tab on the paper, all papers will be maintained in alignment regardless of their size or weight.

The objects and advantages of the invention are as follows:

First, to provide a new method of preparing papers for filing which will assure maintenance of position when used in connection with a single filing post.

Second, to provide a system as outlined in which a special tab is formed on any paper to cooperate with a new form of filing post and functioning to retain the sheet in a substantially fixed position in a file.

Third, to provide a sheet prepared to cooperate with a single filing post and which sheet can be removed or replaced at will without disturbing other sheets in the same file.

Fourth, to provide a filing system and means which is simple in construction and operation, economical to manufacture, and consisting of a minimum number of parts, applicable to conventional letter folders or binder covers, and which permits insertions and removals without disturbing other sheets in the same file or binder.

Other objects and advantages of the invention will become apparent as the following description

is read on the drawing forming a part of this specification, in which:

Fig. 1 is a fragmentary view showing the simplest form of binder with my invention applied thereto, and showing sheets of different lengths filed therein, through the use of a single filing post.

Fig. 2 is a side elevation of Fig. 1.

Fig. 3 is an enlarged sectional elevation taken on line 3—3 of Fig. 1 with the sheets omitted.

Fig. 4 is a transverse section taken through the filing post.

Fig. 5 is an enlarged view of one of the edges of a sheet of paper showing the reinforcement and the entrance slit, and corresponding to a view from line 5—5 of Fig. 1.

Fig. 6 is an enlarged sectional view through the filing post and showing the relation between paper and filing post during filing or removal.

Fig. 7 is a section taken through a portion of a conventional letter file with my invention applied thereto, and is taken on a line 7—7 of Fig. 8.

Fig. 8 is a top plan view of one hinge corner of a letter file with my invention applied thereto.

The invention consists essentially of a holding or securing member comprising mainly a thin flat member of substantial width but preferably of an L-shape or channel or modified channel cross-section having one straight leg with the other leg and the web formed as a continuous curve for ease of insertion and removal of papers therefrom, and a slot formed to fit the flat member or straight leg, or of the same form as the cross-section of the member and located within the body of the material to be filed, near one edge, and with a slit extending from the slot through the adjacent edge of the material to permit removal and replacement of the sheets of material transversely from and onto the securing member, with the portion of the sheet of material in which the slot is formed being reinforced to keep the sheets straight in a binder or file irrespective of the size of the sheet.

The invention is illustrated in connection with both, a loose-leaf binder, and a conventional letter file. The binder is illustrated in its simplest form though the invention is not limited to any specific type of binder cover or letter file or other cover means.

This binder, as illustrated, consists of a top cover 10 which is hinged at 11, the portion 12 of the cover being rigid, and, a bottom cover 13 which is preferably unhinged and rigid throughout, with spacers 14 and 15 suitably securing the

rigid member 12 and the bottom cover 13 in spaced relation.

The filing post 16 is shown as having a straight leg 17 with the other leg and web 18 formed arcuately throughout their combined length. Obviously this filing post may be L-shaped or channel shaped in cross-section, though only illustrated in its preferred form.

This filing post 16 may be secured in position in any suitable manner and is shown as secured at one end in a recess 19 formed in the bottom cover and with the upper end freely fitting in a recess 20 in the top cover 10 to prevent sheets from sliding off over the top of the post.

The sheets or documents can be preformed, or special apparatus (not shown) may be used for forming the required filing slot or passage and for reinforcing the area about the slot, in any sheet of paper or other material to be filed.

The filing slot is preferably formed in the upper left-hand corner of the sheet as indicated in Fig. 1, though it can as readily be located centrally of the length of the sheet, and consists preferably of a modified U-shaped slot formed in the sheet and with a slit extending from the base of the slot to the edge of the paper with one leg of the slot extending from the inner end of the slit in an upward arcuate curve 22, and the other leg 23 of the slot extending upward about the same distance as the arcuate leg and from the point of juncture of the slit 21 and leg 22, thereby forming a tab 24 to fit closely within the body of the filing post 16, with one side 25 straight and the lower edge and other side curved as shown at 26, so that the straight leg 17 of the filing post will be gripped between the edge 25 of the tab 24, and the edge 27 of the external tab 28.

The reinforcement 29 stiffens both tabs 24 and 28, causing the straight leg 17 to be virtually gripped therebetween, though having sufficient flexibility to permit convenient removal and insertion of sheets. This reinforcement is applied before or simultaneously with the slotting operation and may consist of a thickness of cloth or other material adhesively applied, or may consist of a coat of quick-drying lacquer, liquid plastic or varnish, or by dipping this tab portion in a solution of sulphuric acid and drying before slotting. The application of the reinforcement simultaneously with the slotting operation makes it possible to quickly reinforce and slot any sheet of paper, letter, statement, or document, irrespective of its size, and in sequence as they become ready for filing, somewhat as is illustrated in Figs. 1 and 2 in which sheets 30, 31 and 32 of different lengths are shown. This makes the filing system practically universal, requiring only a single file for all sizes of papers to be filed.

As previously pointed out, this invention is equally applicable to binders or ordinary folders as illustrated in Figs. 7 and 8 on an exaggerated scale, and in which the regulation folder is indicated at 33 with its folded back 34 and with the invention mounted therein at 35, for which purpose ears 36 are formed at the respective ends of the filing post, with the ears passing through the folder covers and being bent over to secure the post in position. This filing post can be made of relatively thin material, so that, when made to different lengths, a suitable length can be mounted in the folder, and if it becomes too short for the material filed, it can be removed and a longer post installed.

A sheet is filed by first turning the sheet at right angles to the position it is to occupy in the binder, then advancing and turning the sheet until the tab 24 is located within the body of the binding post 16, the sheet being advanced from the position shown in Fig. 6, which advance flexes the tab 28 which snaps around the outside of the straight leg as the sheet is turned to its normal position in the file as illustrated in Fig. 1. Sheets are removed by merely turning the sheet out and withdrawing.

I claim:

1. A loose-leaf assembly comprising; a sheet having formed in one side thereof a slit extending from the edge of the sheet and terminating in a curved slot, and a branch slot extending from the point of juncture of said slit with said curved slot, and a filing post having a cross-sectional form fitting in said curved and branch slots.

2. A structure as defined in claim 1; and a reinforcement applied throughout the area in which said slots are formed and including the immediate surrounding areas.

3. A loose-leaf assembly comprising a sheet having two adjacent tabs one of which extends to the edge of the sheet and a reinforcement for said tabs; and a binding post of substantially channel shape to fit about the other tab and with one leg secured between the two tabs.

4. A loose-leaf sheet having a slot formed inwardly from one edge and continuing in an upwardly curved slot, and a branch slot formed from said first-mentioned slot at the point of curvature and extending upwardly to approximately the height of said first-mentioned curved slot, to form a tab between said upwardly curved and branch slots receivable in a filing post of similar shape.
